CONTINUOUS MANIFOLDING STRIP SUPPLIES

William J. Wiswall, Portland, Oreg., assignor, by
mesne assignments, to American Sales Book
Company, Inc., a corporation of Delaware

Application January 22, 1929, Serial No. 334,262

35 Claims. (Cl. 282—12)

This invention relates to paper record supplies for manifold recording, more especially to such supplies for use in typewriters, billing machines, autographic registers, and the like.

- 5 One of the objects of the invention is the provision of a practical manifold record supply pack providing a multiplicity of similar sets of printed forms for successive use in machines of the type referred to.
- 10 Another object of the invention is the provision of a simple construction of manifold record supply pack whereby superposed sets of the printed forms are maintained in general registry for advance to the printing point of the machine.

15 Another object of the invention is the provision of a simple, practical and efficient construction of manifold record supply pack whereby superposed sets of printed forms with their carbons are maintained in general superposed registry with each other, but may have a limited longitudinal shift relative to each other for alignment or realignment, in case such shift is needed.

Another object of the invention is the provision of a simple and practical means connecting superposed strips or webs of a manifolding record supply pack of the character referred to, and adapted to restrain departure of the printed forms from predetermined superposed registry, or aligned relation to each other, and which lends itself to ready manufacture and to the various operations of the machine in which the record supply is used.

Other objects of the invention will in part be 35 obvious and will in part appear hereinafter.

The invention accordingly comprises the features of construction, combinations of elements, and arrangement of parts, which will be exemplified in the construction hereinafter set forth 40 and the scope of the application of which will be indicated in the claims.

For a fuller understanding of the nature and objects of the invention reference should be had to the following detailed description taken in 45 connection with the accompanying drawing, in which:

Fig. 1 is a perspective view illustrating an embodiment of the invention;

50 Fig. 2 is an enlarged longitudinal section taken centrally of Fig. 1 substantially normal to the plane of the sheets;

Fig. 3 is a diagrammatic view of a portion of 55 Fig. 1, with the strips greatly separated from each other for clearer disclosure;

Fig. 4 is a view illustrating a section of a transfer traveler web which may be employed;

Fig. 5 is a view illustrating a section of a modified form of transfer traveler web, which may be used alone or conjointly with the transfer 5 web of Fig. 4;

Fig. 6 is an enlarged view of one form of aligner, or web connector, which may be used;

Figs. 7 and 8 illustrate further modified forms 10 of aligner; and

Fig. 9 is a diagrammatic view illustrating the aligner in position in webs which have been shifted relative to each other.

Referring now more specifically to the drawing, the manifolding record supply pack is indicated in zigzag folded condition at 1. The zigzag folds provide a convenient assemblage from which the work web may be drawn or advanced to the typewriter, the billing machine, or the like. It is to be understood, however, that instead of the zigzag folding, the work web might be in rolled form. The work web includes a series of traveler webs, or traveler strips, in superposed relation to each other so as to form a pack or a composite work web.

Referring to Fig. 3, the numerals 2, 3, 4, and 5 indicate foremost sections of four record traveler webs. Interleaved with these record webs are the transfer traveler webs 6, 7, and 8. The transfer traveler webs are adapted to transfer inscription, typewritten or autographic, from the original record web 2 to the underlying record webs 3, 4, and 5, and may be made of the usual carbon paper of commerce, such for instance as the carbons employed for duplicating copies in ordinary typewriting. As illustrated, however, the transfer webs 6, 7, and 8 are carbon coated on their under faces only. The record traveler webs may be made of different colors, the shade lines on the webs 3, 4, and 5 denoting such fact. When the work web thus described is in operative position for receiving inscription, the several webs or strips will be close together as indicated in Fig. 1, the uppermost web or strip 2 being the original, the copy being received upon each of the underlying webs, some of which webs will, of course, be intermediate the undermost web 5 and the original web 2.

The original web 2 will be provided with a series of printed forms, as for instance bill forms, 50 respective of these forms being indicated by the numeral 9. They occur in longitudinal series on the original web, and the underlying webs are provided with similar printed forms so that when in superposed registry with the original forms, 55

inscription made on the latter will be duplicated in the same relative position on the underlying printed forms. When the work web composed of the individual traveler webs and transfer webs is drawn or fed to position in the machine, it will be seen that there is ample opportunity for unrestrained webs to shift longitudinally and laterally relative to each other so that an advance set of superposed forms may shift out of superposed registry relation to each other. One of the objects of the present invention is to restrain such relative shift and on the other hand, when a minimum amount of shift is needed for aligning or registering the forms, to limit the amount of such relative shift.

In the work web is a longitudinal series of strip-controlling apertures, the apertures in the traveler web 2 being indicated by the numeral 10. Each of the underlying traveler webs or strips is provided with a similar series of apertures which is adapted to register or align in superposed relation with the series in the original strip.

The apertures occur at different points in the length of the work web, or pack. Carried by the work web are aperture-engaging and strip aligning members. In the embodiment illustrated, each of these members is indicated by the numeral 11. It passes through the apertures in the several strips, and consequently threads through the apertures in the work web. The member 11 has parts or arms 12 and 13, each of which lies outside the work web, one arm 12 facing the original or upper record traveler web 2 and the other arm 13 facing the lower record traveler web 5, the arms 12 and 13 being fast or secured to the respective traveler webs 2 and 5. In the embodiment illustrated, the aligner members 11 and the arms 12 and 13 thereof are formed of an integral sheet of relatively soft, flexible material, such as paper, which latter may be of the approximate weight of that of the record strips employed. The member 11 and the arms 12 and 13 may be produced by folding an integral sheet of paper, and it will be seen that the arms 12 and 13 lap onto the upper and lower strips of the work web. Thereupon, the arms 12 and 13 are secured to said upper and lower strips respectively as by being pasted to the latter.

By the above described construction it will be seen that as the advance set of forms is gripped and drawn forward, the work web advances from its supply, as the zigzag folds hereinbefore explained, or the roll supply (not illustrated), and each set of superposed forms will be restrained by the aligners 11 from shifting relative to each other, so that superposed registry of printed forms will be substantially maintained for any set arriving at inscribing position. It is to be noted, however, that although the arms 12 and 13 of the strip aligners are firmly secured to the upper and lower traveler strips, nevertheless the member 11 which threads through the traveler strips may bend or fold relative to the respective arms 12 or 13, and thereby permit shift of the traveler strips relative to each other to a controlled degree, as for instance illustrated in Fig. 9, wherein the member 11 has, so to speak, pivoted, as on a hinge, around an edge of the arm 13 of the aligner, and has assumed a position at quite a different angle to the arms 12 and 13 than it has in Fig. 3, which latter illustrates the initial position of the strips before the relative shift therebetween.

It will be seen that the apertures 10 partly transversely divide each of the traveler strips at

points between each two successive sets of printed forms, so as to facilitate tearing the printed forms apart on transverse lines. In addition to the apertures 10, however, each traveler strip is provided with transverse dividing weakening lines 14 leading to the respective apertures 10 and to the points of passage of the strip aligners through the traveler strips. By providing the series of transverse weakening lines 14, the superposed, advance sets of registering printed forms may be parted from succeeding sets along lines which intersect the apertures 10, although it is to be understood that the apertures 10 may be close to the weakening lines 14 instead of being in transverse direct alignment therewith, without departing from the invention. In other words, the apertures 10 through which the strip-aligners or securing devices pass, as well as the securing devices themselves, may be contiguous or in juxtaposition to the respective weakened lines 14. The lines 14 provide weakened severance lines for severing the strips.

In the present embodiment each of the arms of the paper strip aligners lies on the surface of an outer web, and each arm extends from the adjacent aperture of the work web in a direction opposite to the normal direction of advance or feed of the work web through the inscribing machine. In this wise the arms are of little, if any, obstruction to the passage of the work web through the machine. Also in the present embodiment, the strip aligning members thread loosely through the apertures in the strips intermediate the upper and lower strips of the work web, so that the intermediate strips are, as it were, strung on the aligners and are adapted for slight movements on the aligners as the occasion of use may demand. This imparts an added flexibility of relative movement to the strips of the work web. Nevertheless, it is to be understood that such relative movement is provided for by the flexibility of the strip aligner and on account of the different angles which the medial portion 11 of the strip aligner may assume relative to the arms 12 and 13, which latter are fixed to the webs.

In the embodiment illustrated in Figs. 1 and 3, the strip connectors or aligners are substantially U-shaped members, in which the arms 12 and 13 directly overlie each other on the work-web. The U-shaped members may be angular as in Fig. 6, or curved as in Fig. 8. Further, it is to be understood that instead of having the arms 12 and 13 immediately above each other, as in Figs. 3 and 6, one arm may extend in one direction and the other in the opposite direction, as indicated in Fig. 7, wherein the upper and lower arms are respectively indicated by the numerals 15 and 16. When using aligners of the type illustrated in Fig. 7, and in which transverse weakening lines lead up to the relevant apertures in the strips, one or another, or both, or the arms 15 and 16 may be weakened, as indicated by the dotted lines 17 and 18, so as readily to be parted during the tearing operation. When the form of aligner illustrated in Fig. 6 or Fig. 8 is employed, the intermediate portion 11 thereof practically coincides with the weakened line in the strip and does not require being torn. By employing the attaching aligner of the type illustrated in either Fig. 6 or Fig. 8, the upper and lower sheets of the parted set of forms will be positively connected to each other by the aligner portion 11, and the intermediate sheets will be more or less removably held in

place against other than deliberate separation from the parted set.

In the form illustrated, the apertures through the work-web are disposed along the central longitudinal line of the web, but it is to be understood that the apertures may be located at the sides of the web without departing from the broad inventive concept.

Referring to Fig. 3, it will be seen that the record webs 2, 3, 4, and 5 each has a series of notches or openings in its edge, these notches being generally indicated by the numerals 18, whereas the transfer strips 6, 7, and 8 intercept these notches 18 at one side of the work web. At the opposite side of the work web the transfer strips are provided with a series of notches 19 which are intercepted by the record strips. In other words, marginal portions of the transfer strips are aligned with the notches 18 depthwise of the assembly at one part of each set of leaves or forms, while marginal portions of the record strips or webs are similarly aligned with the notches 19 at another or spaced point of each said set. It will be noted also that the grip-forming apertures or notches 18 and 19 are positioned only in the vicinity of alternate weakening division lines 14 in the respective record and transfer strips, preferably extending to points both forwardly and rearwardly of the respective division lines and symmetrically arranged with reference thereto. The apertures in each of the strips are thus longitudinally spaced apart distances equal to the combined length of the two form leaves or sheets. The grip forming apertures 18 and 19 are arranged in sets depthwise of the work web or record assembly and are respectively aligned with marginal portions of adjacent strips which thus form selective grip areas. The apertures 19 of the transfer strips are preferably longitudinally offset in the assembly one leaf length from the record strip apertures 18 so that the selective grip formations provided by these apertures are positioned at diagonally opposite corners of each of the leaf sets. The weakened severance or division lines 14 are, as shown, preferably arranged one above another in groups positioned at form length intervals along the assembly thus facilitating severance of the leaf sets along the respective groups. When an advance set of forms is parted from the work web, all the superposed transfer sheets thereof may be grasped through the notches 18 without grasping the record sheets, whereas the record sheets may be grasped adjacent the notches 19 without grasping the transfer sheets. Consequently, a slight pull in opposite direction will immediately separate all the transfer sheets from the inscribed record sheets.

It will be observed that in the embodiment disclosed all the traveler webs or strips are flexibly connected together in a manner to permit longitudinal shift of individual webs relative to each other to a limited degree, whereas the flat paper members 11 of the connecting means offer considerably greater resistance to flexing laterally and thereby tend more strongly to retain the record strips in lateral alignment with each other. In this connection it will be noted, as shown in Figs. 1 and 3, that each of the strip fastening and aligning members 11 is preferably of a width to substantially bridge the corresponding aperture 10. The members 11 will thus contact at their lateral edges with the corresponding strips at the ends of said apertures,

thus holding both the record and transfer strips at all times in lateral alignment with each other.

An important feature of the invention is the association of the transfer material with the record traveler webs in a work-web of which the plies are controlled by the aligners, as already explained. In the embodiment illustrated, each record traveler web and each transfer traveler web is a continuous paper strip, one being coated or embodying the transfer material, as 10 carbon transfer material. It is to be understood, however, that, instead of using a continuous, transfer traveler web, individual and distinct from the record web, the record web may be carbon coated on its under face, or may have a 15 longitudinal series of short strips or sheets of transfer paper attached as by spots of paste to the under face of the much longer record traveler web, without departing from certain aspects of the invention. 20

Since certain changes may be made in the above construction and different embodiments of the invention could be made without departing from the scope thereof, it is intended that all matter contained in the above description or 25 shown in the accompanying drawing shall be interpreted as illustrative and not in a limiting sense.

Having described my invention, what I claim as new and desire to secure by Letters Patent is: 30

1. A manifolding, recording pack of the character described including, in combination, a composite traveler work-web including a plurality of relatively superposed strips and having a longitudinal series of strip-control apertures, and 35 strip-aligners carried by the work-web and engaging in the respective control apertures, each of said strip-aligners being composed of a single integral sheet member, said aligners loosely threading through said apertures of the intermediate strip or strips of said work-web and being fast to the upper and lower strips thereof. 40

2. A manifolding, recording pack of the character described including, in combination, a composite traveler work-web including a plurality of 45 relatively superposed strips and having a longitudinal series of strip-control apertures, and strip-aligners carried by the work-web and engaging in the respective control apertures, said aligners respectively including a flexible sheet member with the plane of its aperture engaging 50 part disposed transversely of the work-web and being of relatively soft material folded to lap onto the upper and lower strips of the work-web.

3. A manifolding, recording pack of the character described including, in combination, a composite traveler work-web including a plurality of 55 relatively superposed strips and having a longitudinal series of strip-control apertures closed by the strip material, and strip-aligners carried by the work-web and engaging in the respective control apertures, said aligners respectively including an aperture-engaging frangible sheet member having arms overlapping and fast to the upper and lower strips of the work-web. 60

4. A manifolding, recording pack of the character described including, in combination, a composite traveler work-web including a plurality of 65 relatively superposed strips and having a longitudinal series of strip-control apertures, and 70 strip-aligners of frangible material carried by the work-web and engaging in the respective control apertures, said aligners respectively including an aperture-engaging member having arms fast to the upper and lower strips of the work-web and 75

extending from the aperture away from the advance end of the work-web.

5. A manifolding, recording pack of the character described including, in combination, a composite traveler work-web having a longitudinal series of strip-control apertures and strip-controlling, flexible, sheet paper members threading through the respective apertures and having their aperture engaging planes disposed transversely of the work-web.

6. A manifolding, recording pack of the character described including, in combination, a traveler work-web having a longitudinal series of strip-control apertures, and strip-controlling, flexible, paper members threading through the respective apertures, and pasted to the faces of the work-web.

7. A manifolding, recording pack comprising a series of traveler strips superposed relative to each other and including record traveler strips and one or more transfer traveler strips, and separate, strip-controlling, sheet members passing through said traveler strips at a series of different points in the length of the pack, said sheet members being secured only to the upper and lower strips, and the planes of the parts thereof passing through the strips being disposed transversely of the traveler strips.

8. A manifolding, recording pack comprising a series of traveler strips superposed relative to each other and including record traveler strips and one or more transfer traveler strips, and separate, strip-controlling, paper members passing through said traveler strips and secured to certain thereof at a series of different points in the length of the pack, said paper strip-controlling members being in the form of sheets and having the widths of the parts thereof which pass through the strips extending transversely thereof, said traveler strips each having transverse, weakening lines leading to the respective points of passage of said strip-controlling members.

9. A manifolding, recording pack of the character described including, in combination, a traveler work-web and flexible means connecting its individual webs relative to each other at each of a series of different points in the length of the work-web, said connecting means being flexible and yieldable longitudinally of the pack so as to provide for longitudinal shift of said individual webs relative to each other, to a controlled degree, at each of said points.

10. A manifolding recording pack comprising a series of record traveler strips and one or more transfer traveler strips in superposed relation to each other and having transverse severance lines for parting successive relatively superposed sections from the pack, means restraining said strips in aligned superposed registry with each other whereby parting said sections from the pack along said lines will free the parted sections of transfer strip for being drawn from superposed relation to the parted record strip sections, said means including control apertures in said transfer strip or strips, coincident with said lines, and flexible strip-aligners of sheet material carried by the pack and engaging in said apertures with their widths disposed transversely of the strips.

11. A manifolding, recording pack of the character described including, in combination, a composite traveler work-web including a plurality of relatively superposed strips and having a longitudinal series of strip-control apertures, and strip-aligners carried by the work-web and engaging in the respective control apertures, each

of said strip-aligners being composed of a single integral sheet member, said aligners loosely threading through said apertures of the intermediate strip or strips of said work-web and being fast to the upper and lower strips thereof, and said aligners being free from attachment with the strips intermediate said upper and lower strips of the pack.

12. A manifolding, recording pack of the character described including, in combination, a composite traveler work-web including a plurality of relatively superposed strips and having a longitudinal series of strip-control apertures, and strip-aligners carried by the work-web and engaging in the respective control apertures, said aligners respectively including an aperture-engaging member having arms fast to the upper and lower strips of the work-web, one of said arms of each aligner extending from the aperture away from the advance end of the work-web and another arm thereof extending from the aperture toward the advance end of the work-web.

13. A manifolding record pack including a transversely folded traveler multi-ply work-web including a plurality of record form strips in superposed relation to each other for manifolding inscription, and having transverse lines to provide successive sets of relatively superposed form sections, transfer material interposed between the record strips throughout the length of the work-web, the forms of each set being longitudinally shiftable relative to each other on folding the set, said work-web, at each of a number of separate points throughout its length having a longitudinally yieldable connecting device of sheet material yieldably restricting the extent of said relative shift consequent from folding the set.

14. A manifolding record assembly including a traveler multi-ply work-web including a plurality of record form strips in superposed relation to each other for manifolding inscription and each having a longitudinal series of record forms, transfer material interposed between the record paper strips throughout the length of the work-web, said work-web, at each of a number of separate points throughout its length, having a longitudinally yieldable connecting device of sheet material cooperative to restrict the extent of relative shift in one direction longitudinally of the work-web and to arrest the forms of a set in predetermined superposed position relative to each other, and means whereby said connecting device provides for relative shift in the opposite direction between the forms of said last mentioned set.

15. A manifolding assembly including a traveler multi-ply work-web folded zigzag to provide a compact packet, and including a plurality of relatively superposed, folded, record strips having forms providing successive sets of relatively superposed forms throughout the length of the work-web, said packet, at each of a number of separate longitudinally spaced points throughout the length of the folded work-web, having a longitudinally yieldable connecting device of sheet material permitting but restricting the extent of relative longitudinal shift between said superposed strips consequent from unfolding the work-web.

16. A manifolding assembly including a traveler multi-ply work-web folded zigzag to provide a compact packet, and including a plurality of relatively superposed, folded, record strips having forms providing successive sets of relatively super-

- posed forms throughout the length of the work-web, said packet, at each of a number of separate longitudinally spaced points throughout the length of the folded work-web, having a longitudinally yieldable connecting device of sheet material permitting but restricting the extent of relative longitudinal shift between said superposed strips consequent from unfolding the work-web, said connecting device having parts interengaging laterally with the work-web to maintain said strips of each set against lateral shift relative to each other both in the packet and when the work-web is unfolded.
17. A manifolding pile comprising a plurality of continuous record or worksheet strips and a continuous transfer strip interposed between two adjacent record strips in manifolding relation, said strips being divided at regular intervals by transverse weakening lines to form a succession of units each consisting of record sheets and an interleaved transfer sheet, the transfer sheet of each unit having an aperture inwardly removed from its lateral edges, said aperture being in part bounded by a line of weakening, and fastening means for coupling the record sheets of each unit together, said means passing through the respective apertures.
18. A supply for manifold use including, in combination, a pair of continuous record strips in superposed relation to each other, a third continuous strip intermediate the webs of said pair adapted to travel therewith, said intermediate strip having a longitudinal succession of completely circumscribed holes and the strips of said pair, at intervals coincident with said holes, being coupled for traveling one with the other, the strips having transverse dividing lines along which they may be severed into sheet-lengths, each dividing line in the intermediate web forming a part of the edge of one of said holes so as to open a side of the hole when the strips are severed along said dividing lines.
19. A supply for manifold use including, in combination, a pair of strips in superposed relation to each other, a third strip intermediate the strips of said pair adapted to travel therewith, said intermediate strip having a longitudinal succession of holes inwardly removed from its side edge and completely circumscribed, and means attaching said strips of said pair together through said holes, the strips having transverse dividing lines along which they may be severed into sheet-lengths, each dividing line in the intermediate web forming a part of the edge of one of said holes so as to open a side of the hole when the strips are severed along said dividing lines.
20. Superposed record strips and a transfer strip therebetween, said transfer strip having transverse dividing lines at sheet-length intervals and an internal completely circumscribed hole, an edge of which is constituted by said dividing lines, and fastening means, coincident with said hole, securing record strips together.
21. A manifolding recording pack of the character described including, in combination, a composite traveler work-web having a longitudinal series of strip-control apertures inwardly removed from its longitudinal edges, said work-web also having a longitudinal series of transverse weakening lines, and strip-aligners carried by the work-web and engaging in the respective control apertures, respective of said apertures being in transverse alignment with respective of said weakening lines.
22. A manifold assembly, including in combination, a plurality of relatively superposed continuous strips including a plurality of continuous record strips and at least one continuous transfer strip interleaved in transfer relation with the record strips, said transfer strip having a plurality of longitudinally spaced apertures formed therein and being inwardly removed from the longitudinal edges thereof, and a plurality of securing devices securing said record strips together in the assembly and extending respectively through said transfer strip apertures so as to hold the transfer strip in position in the assembly.
23. A manifold assembly including, in combination, a plurality of relatively superposed continuous strips including a plurality of continuous record strips and at least one continuous transfer strip interleaved in transfer relation with the record strips, said transfer strip having a plurality of longitudinally spaced apertures formed therein and being inwardly removed from the longitudinal edges thereof, and a plurality of securing devices having direct attachment with said record strips and extending respectively through said transfer strip apertures so as to secure all of the strips together in the assembly, said securing devices being freely received in the respective apertures.
24. A manifolding pile comprising a plurality of superposed continuous record strips and interleaved transfer strips having registering transversely disposed lines of weakness along which the pile may be severed to form sets of superposed record and transfer sheets; and means located on the lines of weakness for holding the strips in registration in the pile until the pile is severed, said means engaging the strips beyond the lines of perforations for temporarily holding the sheets of a severed set together against casual separation.
25. A manifolding pile comprising a plurality of superposed continuous record strips and interleaved transfer strips having registering transversely disposed lines of weakness along which the pile may be severed to form sets of superposed record and transfer sheets; and strips of sheet material passing through the pile of strips flatwise on the line of perforations and bent to lie on the top and bottom strips and engaging the pile of strips to hold the strips in registration preparatory to and during the operation of writing upon the strips.
26. A manifolding pile comprising a plurality of superposed continuous record strips and interleaved transfer strips having registering transversely disposed lines of weakness along which the pile may be severed to form sets of superposed record and transfer sheets; and means located on the lines of weakness for holding the strips in registration in the pile until the pile is severed, said means each embracing the material of the strips at one side of its lines of severance to cling to the strips when they are severed.
27. A record pack including a work web having a plurality of record traveler strips and one or more transfer traveler strips in superposed relation to each other, and having transverse weakened severance lines for parting successive relatively superposed sections from the work web, said record and transfer strips having apertures respectively contiguous to said severance lines and being elongated transversely of the strips, and means including strip aligners of sheet material carried by the work web for restraining said strips in aligned, superposed registry with each other, said aligners passing respectively through

said apertures with their widths extending transversely of the strips, whereby parting of said sections from the work web along said severance lines will free the parted sections of transfer strip 5 whereby they may be drawn from superposed relation with the parted record strip sections.

28. A manifolding assembly, including in combination, a plurality of relatively superposed continuous strips including a plurality of continuous 10 record strips and at least one continuous transfer strip, interleaved in transfer relation with each other, said record and transfer strips having transverse weakened severance lines arranged in groups and longitudinally spaced at substantially 15 ly form length intervals, said record strips being formed along one of the longitudinal edges thereof with selective grip notches positioned only at alternate groups of severance lines, said transfer strip or strips being formed with grip notches 20 along the longitudinal edge thereof, at the assembly edge opposite to said first mentioned grip notches and positioned only at alternate groups of the severance lines and only at the said groups which are longitudinally spaced from the groups 25 at which the first mentioned notches are located, said notches in the record and transfer strips being formed in each instance so as to extend into the strip material at each of the opposite sides of the severance lines, and exposing aligned strip 30 portions so as to provide selective grip formations at each of the opposite sides of said severance lines.

29. A manifolding assembly including a plurality of relatively superposed continuous strips, 35 each having a series of transverse division lines dividing the respective strips into a series of leaves and forming a series of sets of relatively superposed leaves, respective corresponding division lines of the several strips being relatively superposed in the assembly, said strips having longitudinally spaced selective grip-forming apertures positioned only in the vicinity of alternate division lines of the respective strips, and each of said apertures being positioned in depthwise alignment with gripping areas of the adjacent strip. 45

30. A manifolding assembly including a plurality of relatively superposed continuous strips, each having a series of transverse division lines dividing the respective strips into a series of leaves 50 and forming a series of sets of relatively superposed leaves, respective corresponding division lines of the several strips being relatively superposed in the assembly, said strips having longitudinally spaced selective grip-forming apertures positioned substantially symmetrically with reference to the opposite sides of the respective division lines and only in the vicinity of alternate division lines of the respective strips, and positioned only in alternate strips depthwise of the 55 assembly at the different successive division lines thereof.

31. A manifolding assembly including a plurality of relatively superposed continuous strips, each having a series of transverse division lines, 60 dividing the respective strips into a series of leaves and forming a series of sets of relatively superposed leaves, respective corresponding division lines of the several strips being arranged in groups in the assembly, said strips having longitudinally spaced selective grip-forming apertures 65

positioned only in the vicinity of alternate division lines of the respective strips, and positioned only in alternate strips depthwise of the assembly at the different successive division lines thereof, said grip-forming apertures being relatively superposed at the successive division lines and extending to points both forwardly and rearwardly of the respective division lines so as to expose gripping areas of the next adjacent strip both forwardly and rearwardly of the division lines. 10

32. A manifolding assembly having a plurality of relatively superposed continuous strips including a plurality of continuous record strips and at least one continuous transfer strip interleaved in transfer relation with the record strips, each of 15 said record and transfer strips having a series of transverse division lines dividing the respective strips into a series of leaves so as to form a series of sets of relatively superposed record leaves with interleaved transfer leaves, the strips 20 of said assembly being formed with selective grip-forming apertures arranged in sets and the apertures of each set being in superposed relation with each other, said apertures being provided only in the vicinity of alternate division lines in the respective strips, and the apertures of the superposed sets being provided only in alternate strips 25 depthwise of the assembly.

33. A manifolding assembly, including in combination, a plurality of relatively superposed continuous strips including a plurality of continuous record strips and at least one continuous transfer strip interleaved in transfer relation with the record strips, each of said record and transfer strips having a series of transverse division lines 35 dividing the respective strips into a series of leaves so as to form a series of sets of relatively superposed record leaves with interleaved transfer leaves, the strips of said assembly being formed with selective grip-forming apertures arranged 40 in sets and the apertures of each set being in superposed relation with each other, said apertures being provided only in the vicinity of alternate division lines in the respective strips, and the apertures of the superposed sets being provided 45 only in alternate strips depthwise of the assembly. 50

34. A transfer strip having transverse division or fold lines arranged in a longitudinal series and dividing the strip into a series of leaves, said strip having a plurality of grip-forming apertures 55 arranged in a longitudinal series and positioned only in the vicinity of alternate division lines, and each aperture having parts thereof lying at opposite sides of the respective division line.

35. A manifolding assembly including, in combination, a plurality of relatively superposed continuous strips, each having a series of leaves positioned one after another therealong, said leaves being relatively superposed to form a series of leaf sets positioned along the assembly, each of said 65 strips having a longitudinal series of selective grip-forming apertures longitudinally spaced apart substantially the combined lengths of two of said leaves. 60
